(57) **CLAIM**

The ornamental design for a solar lead wire and multi-wire clip or portion thereof, as shown and described.

DESCRIPTION

FIG. 1 is a perspective view of a solar lead wire and multi-wire clip, showing our new design therefor;

FIG. 2 is a front view thereof;

FIG. 3 is a back view thereof;

FIG. 4 is a left side view thereof;

FIG. 5 is right side view thereof;

FIG. 6 is a top view thereof; and,

FIG. 7 is a bottom view thereof.

The broken lines shown in the figures are for illustrative purposes only and form no part of the claimed design. The broken lines show alternative embodiments of some features in an alternative broken line disclosure.
